[57] **CLAIM**

The ornamental design for an automobile, as shown and described.

DESCRIPTION

FIG. 1 is a front perspective view of an automobile embodying my novel design;

FIG. 2 is a rear perspective view thereof;

FIG. 3 is a left side elevation view thereof;

FIG. 4 is a right side elevation view thereof;

FIG. 5 is a left side perspective view taken from the rear thereof;

FIG. 6 is a left side perspective view taken from the front thereof; and,

FIG. 7 is a top perspective view thereof.

The broken line showing of environmental structure in FIGS. 1, 2, 5, 6 and 7 of the drawing is for illustrative purposes only and forms no part of the claimed design.

FIG. 1**FIG. 2**FIG. 3

FIG. 4

FIG. 5FIG. 6

FIG. 7
